(57) **CLAIM**

We claim the ornamental design for an entry shroud, as shown and described.

DESCRIPTION

FIG. 1 is a top perspective view of the entry shroud.

FIG. 2 is a bottom perspective view of the entry shroud.

FIG. 3 is a front view of the entry shroud.

FIG. 4 is a rear view of the entry shroud.

FIG. 5 is a top view of the entry shroud.

FIG. 6 is a bottom view of the entry shroud.

FIG. 7 is a side view of the entry shroud; and,

FIG. 8 is a side view of the entry shroud.

In the drawings, the broken lines illustrate environment and forms no art of the claimed design.
